195,341

MOBILE BAR

Joseph A. Reymann, 403 Canton Road, Akron, Ohio

Filed Feb. 9, 1962, Ser. No. 68,743

Term of patent 7 years

(Cl. D33—19)

FIG.1

FIG.2

FIG.3

FIG. 1 shows a perspective view of a mobile bar showing my design;

FIG. 2 is a rear elevation of the mobile bar of FIG. 1 with a compartment lid open; and

FIG. 3 is a rear elevation, like FIG. 2, but with the compartment lid closed.

I claim:

The ornamental design for a mobile bar, as shown.

References Cited in the file of this patent

UNITED STATES PATENTS

- D. 88,706 Garton ----- Dec. 20, 1932
D. 89,857 Garton ----- May 9, 1933

OTHER REFERENCES

The Home Craftsman, March-April 1961, p. 14, top center, barrel cart by P. H. Morrison.

Premium Practice, Dec. 1937, p. 28, left center, item No. 50, end table.